James H. Webber

INVENTOR

BY Victor J. Evans

ATTORNEY

WITNESS:

J. T. L. Wright

UNITED STATES PATENT OFFICE.

JAMES H. WEBBER, OF CARROLLTOWN, PENNSYLVANIA.

ATTACHMENT FOR ARCTICS.

Application filed June 11, 1926. Serial No. 115,332.

This invention relates to an attachment for the tops of arctics and galoshes, the general object of the invention being to prevent the tops of the arctics from soiling the stockings of the user, by preventing the upper portions of the arctics from coming in contact with the stockings.

Another object of the invention is to provide the device with frictional means for holding it in place at the top of the arctic.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:—

Figure 1 is a view of an arctic, with parts broken away, showing the invention in use.

Figure 2 is a view of the device itself.

Figure 3 is a top plan view of the device.

Figure 4 is a sectional view through the upper part of Figure 1.

Figure 5 is a similar view but taken at right angles from that of Figure 4.

As is well known, arctics or galoshes which extend above the shoes will soil the stockings of the user, and it is the object of my invention to prevent this by providing an attachment which is placed in the top part of the arctic in such a manner that it will prevent the arctic from contacting with the stocking. This device comprises a body 1 of substantially cylindrical form, with its ends overlapping, as shown at 2. The upper edge of the body is rolled, as at 3, so that it

will pass over the upper edge of the arctic and grip the same and thus frictionally hold the device to the arctic. The device is preferably formed of celluloid or similar material so that it is of a springy nature. The rolled part terminates short of the ends, but these ends have their upper edges extended upwardly slightly, as shown at 4. By overlapping the ends, the device can be made to fit various sizes of arctics as it is simply necessary to cut off the ends if the device is too large so that the overlapping part will not be excessive.

This device will not only act to protect the stockings but it will also act to prevent dirt, snow and the like from entering the arctic between the top thereof and the leg of the wearer.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:—

1. An attachment for an arctic formed of semi-rigid and springy material and comprising a cylindrical body adapted to fit within the upper end of the arctic and a rolled top for receiving the upper edge of the arctic and frictionally engaging the same.

2. An attachment for an arctic formed of celluloid and comprising a cylindrical body having overlapping ends, with portions of its upper edge rolled to receive and frictionally engage the upper edge of an arctic.

In testimony whereof I affix my signature.

JAMES H. WEBBER.
